(57) **CLAIM**

The ornamental design for a biometric interface for a locking mechanism, as shown and described.

DESCRIPTION

FIG. 1 is a left front perspective view of our new biometric interface for a locking mechanism according to the present invention;

FIG. 2 is a front view of the biometric interface shown in FIG. 1;

FIG. 3 is a top view of the biometric interface shown in FIG. 1;

FIG. 4 is a bottom view of the biometric interface shown in FIG. 1;

FIG. 5 is a left side view of the biometric interface shown in FIG. 1; and,

FIG. 6 is a right side view of the biometric interface shown in FIG. 1.

The broken lines showing the lock handle and lock in FIGS. 1–6 are for illustrative purposes and form no part of the claimed design.

The broken line(s), which define the bounds of the claimed design, form no part thereof.
